CONTROL MECHANISM FOR LOOM
STOP MOTIONSJoseph P. Costello, Philadelphia, Pa., assignor to
Collins & Aikman Corporation, Philadelphia,
Pa., a corporation of Delaware

Application May 2, 1933, Serial No. 668,912

9 Claims. (Cl. 139—340)

My invention is an improved mechanism for controlling the operation of a loom or similar apparatus, and it is particularly designed to provide means for stopping the operation thereof upon the completion of the weaving of the number of picks which can be woven from a cop of known length. The shuttle is stopped in proper position for the resumption of weaving upon the insertion of a fresh bobbin or cop and the control mechanism is reset without any special attention on the part of the weaver, who may also reverse the motion to "pick back" or unweave a defectively woven fabric section without interfering with the proper functioning of the stop mechanism upon exhaustion of the yarn on the bobbin in use.

By my improvements, a yardage of yarn sufficient for a number of picks of predetermined length to weave a fabric of desired width may be wound upon a bobbin, and the loom stopped upon or immediately before the substantial exhaustion of the yarn, with avoidance of defects in the fabric and of wastage of yarn and time. The mechanism is readily adjustable to permit the use of various lengths of yarn on a bobbin or the weaving of fabrics of different widths, and may be so set as to stop the loom when the shuttle is in a desired box of the loom and just prior to the exhaustion of the yarn thereon.

In the preferred embodiment of my invention, an adjustable measurer or pick counter is provided movable in synchronism with the throws of the shuttle and at a predetermined point in its movement permits the actuation of the loom control lever when the yarn retained on the bobbin is insufficient to complete another pair of picks.

My invention is particularly applicable to a usual form of loom having its stop motion, such as a belt shifter or electric switch, operable by a handle or lever. In accordance with my improvements, this handle or lever is shifted by an arm or bracket carried by the loom frame and having thereon an oscillatory member, such as a dagger, which, when engaged by a loom member, such as a part of the lay, operates the arm or bracket to shift the control lever or handle.

The movement of the loom control lever or handle to the "go" position moves the oscillatory member or dagger out of the path of the actuating lay member and latches the dagger in such disengaging position. The latching mechanism is tripped to permit the lay member to engage the oscillatory member on the bracket under control of a belt operable in synchronism with the

loom shuttle mechanism or the beat of the loom. The belt may be varied in length and preferably consists of an endless sprocket chain movable one link for each complete reciprocation of the shuttle. The control of the latching mechanism by the belt is preferably effected through a circuit containing an electromagnet for tripping the latching mechanism, the circuit being opened or closed by a contact carried on or operable by the chain.

The characteristic features and advantages of my improvements will more fully appear from the following description and the accompanying drawings in illustration of a preferred embodiment of my improvements applied to a conventional double shuttle loom.

In the drawings, Fig. 1 is a fragmentary top plan view of one end of a double plush loom having my improvements applied thereto, with the parts in the position occupied when the loom is at rest; Fig. 2 is a side elevation of the mechanism shown in Fig. 1 with the parts in the position occupied when the loom is in motion; Fig. 3 is a diagrammatic perspective view of mechanism comprised in my improvements detached from the loom and in the position shown in Fig. 2; Fig. 4 is a detail view of a worm and screw device employed in the mechanism; Fig. 5 is a side elevation of a modified form of structure shown in previous figures, and Fig. 6 is a view partially in section and partially in top plan of the structure shown in Fig. 5.

As illustrated in the drawings, my improvements are applied to a usual type of double shuttle loom suitable for the weaving of plush. My improvements are, however, also applicable to other types of looms and to other mechanisms.

In the embodiment of my improvements illustrated in the drawings, a main shaft 1 has fixed thereon a worm 2 by a pawl 51' pivoted on the hub 46' of the worm 2 as shown in Figs. 3 and 4 which meshes with and rotates a worm gear 3 fixed to the shaft 4 journaled in the adjustable brackets 5 and 6. The ratchet 50' is integral with the hub 46' and during forward weaving of the loom the pawl 53', pivoted on a fixed element of the loom, will idle over it as the shaft 1 turns. If the loom is reversed, the pawl 51' will disengage and release the worm from the shaft, whereas pawl 53' will prevent rearward rotation of the worm 2. Thus it is seen that the measuring device is rendered inoperative during unweaving to correct weaving defects. A collar 52' is positioned on the shaft 1 by a set screw to prevent axial movement of the clutch mem-

bers. The upper end of the shaft 4 has fixed thereto a worm 1 which meshes with and rotates the worm wheel 8 fixed on the transverse shaft 9. A sprocket 10, fixed on the shaft 9, has looped thereon an endless sprocket chain 11 composed of links which may be readily attached and detached to vary the length of the chain loop.

A contact 12 is fixed to the chain 11 and is adapted for engagement with a contact member 13 mounted upon an insulating block 14 on a frame member of the loom. The engagement of the contact 12 with the contact 13 closes a circuit comprising a source of electricity, such as the battery 15, a conductor 16 connecting the battery with the contact 12 through the sprocket 10, and chain 11, and a conductor 17 connecting the contact 13 with the coil of an electromagnet or solenoid 18, which has its other end connected by a conductor 19 with the battery 15.

20 The rotation of the sprocket wheel 10 is so synchronized with the rotation of the shaft 1 that the chain 11 moves a distance equal to one link for each complete throw of the shuttles back and forth, consequently the circuit is closed by 25 the engagement of the contact 12 with the contact 13 only when the shuttles are in their boxes at the right hand or operating side of the machine and after twice as many picks have been woven as there are links in the chain.

30 A usual type of loom stop motion such as a switch or belt shifter (not shown) is controlled by the spring lever 20 fixed to the loom frame. The upper portion of the lever 20 is provided with a handle 21 and is movable in a frame slot 22 having a widened portion 23 forming a notch in which the lever is engaged in the "go" position. When the lever is disengaged from the notch 23, it springs by its own elasticity to the position shown in Fig. 1 thereby operating a belt shifter, 40 switch or other stop motion to stop the loom.

The lever 21 may be disengaged from the notch 23 manually or by the action of an arm or bracket 24 carried by and rocking on the frame. The arm or bracket 24 is operable, to disengage the lever 45 20 from the notch 23, by a reciprocable member 25 of the loom, such as a sword or motion operated in synchronism with the shuttle carrier or lay. The member 25 rocks the arm 24 when the step member 26 thereof (Figs. 1 and 3) comes into 50 contact with the end of the arm or dagger 27 of the shaft 28. The shaft 28 is journaled in bearings 29 of the bracket 24 and has fixed thereon a latch member 30 (Fig. 3) cooperating with a latch member or lever 31 pivoted on the bracket 24. The end 32 of the lever 31 is so counter-weighted that it normally rocks the latch or lever 30 and shaft 28 to elevate the end of the dagger 27 above the path of the step member 26.

When, however, the circuit of the solenoid 60 coil 18 is closed by the engagement of the contact 12 with the contact 13 the armature 33 is elevated and acts through the bearing 34 thereon against the pin 35 fixed to the end 32 of the lever 31 and rocks the latter out of engagement with the latch 30. The end of the dagger 27 thereupon drops into position for engagement by the 65 step 26 of the sword 25 and rocks the bracket 24 to disengage the lever 20 from the notch 23. The lever 23 thereupon springs to its "off" position and causes the stop motion to stop the loom.

When the lever 20 is again moved by its handle 21 to the right (Figs. 1 and 3) to place the stop mechanism in the "go" position, it shifts the arm or bracket 24 away from the slot 22 and the pin 36 70 on the lever 20 depresses the arm 37 projecting

from the crank arm 38 of the shaft 39 journaled in bearings 40 of the bracket 24. The shaft 39 has fixed thereto an arm 41 from which depends a hooked link 42 looped over the pin 43 on the arm 44 of the latch 30. The rocking of the shaft 5 39 acts through the parts to elevate the latch 30.

The rocking of latch 30 acts through the shaft 28 to elevate the arm 27 out of the path of the reciprocating step 26 and as soon as the contact 12 disengages from the contact 13 the latch 31 engages the latch 30 and the loom continues to run until the stop lever is again actuated by the mechanism described or manually. The manual operation of the lever 20 to the "off" position has no effect upon the automatic control mechanism. 15

In the modification of the invention shown in Figs. 5 and 6, in which corresponding parts are designated by corresponding reference characters, the shaft 4' has loosely thereon a sleeve 46 having a worm screw portion 47 engaging a worm wheel 48 on a pintle 49; the sleeve 46 also having fixed thereto a notched collar 50 for engagement in one direction of rotation of the shaft 4' by a spring biased pawl 51 in a sleeve 52 secured to the shaft 4. A pawl 53 supported on a stationary part of 25 the frame and positioned by an element 54 cooperates with notches 55 in the side of the sleeve 50.

When the shaft 4' rotates in one direction, the pawl 51 drives the worm screw 47 through the 30 collar 50; the pawl 51 in this direction of rotation slipping over its notches. In the reverse or unweaving direction of rotation of the shaft 4', the pawl 51 slips over its notches in the sleeve 50 which is held against reverse rotation by the pawl 53, thus preventing deductions from a count made while the sleeve 46 is rotating in the forward or weaving direction. 35

Having described my invention, I claim—

1. In combination on a loom, a shuttle containing a measured weft supply package, mechanism for effecting the stoppage of the loom upon or just before the exhaustion of the predetermined length of weft from the supply package, comprising a sprocket, a rotatable shaft carrying said sprocket, means comprising a pair of oppositely acting latch members for rotating said shaft in synchronism with the beat-up operation of the loom upon the movement of the loom in weaving, said means permitting movement of said loom in unweaving without affecting movement of said shaft, an endless sprocket chain of variable length mounted on said sprocket and movable thereby one complete length of the chain during the laying of the predetermined length of weft in a given number of beat-up operations of the loom, a knock-off device operable by said chain for effecting the stoppage of the loom, a starting handle, and means operable by the movement of said starting handle to running position 60 for automatically resetting said knock-off device. 55

2. In combination on a loom having a weft supply package of a predetermined measured length, a loom stop motion operating to stop the loom upon or just before the exhaustion of the 65 measured length of weft from the supply package, regardless of the number of pick outs made during the weaving in of said weft supply package, comprising a movable member, a device controlling the stopping of the loom and movable 70 into and out of the path of said member, means comprising an endless measuring belt for controlling the movement of said device and means operable in synchronism with the beat-up of the loom for advancing said belt upon the operation 75

of said loom for weaving, means comprising a pair of oppositely acting latch members for advancing said endless belt when the loom is weaving but which is rendered inoperative when the loom is reversed for picking out or unweaving.

5. In combination on a loom having a weft supply package of a predetermined measured length, a loom stop motion operating to stop the loom upon or just before the exhaustion of the measured length of weft from the supply package, regardless of the number of pick-outs made during the weaving in of said weft supply package, comprising a movable member, a belt, a device controlling the stopping of the loom and movable into and out of the path of said member, a circuit containing an electro-magnet, a contact operable by said belt for controlling said circuit, latching mechanism operable by the electro-magnet of said circuit, a dagger controlled by said latching mechanism, an arm operable by said dagger, a shipper handle operable by said arm, and means operable by said shipper handle for moving said dagger and setting said latching mechanism upon movement of the handle toward starting position, and means comprising two oppositely acting latch members for advancing said belt when the loom is weaving but which is rendered inoperative when the loom is reversed for picking out or unweaving.

30. 4. In combination on a loom having a weft supply package of a predetermined measured length, a loom stop motion operating to stop the loom upon or just before the exhaustion of the measured length of weft from the supply package, regardless of the number of pick-outs made during the weaving in of said weft supply package, comprising a movable member, a movable contact, a device controlling the stopping of the loom and movable into and out of the path of said member, means comprising an electric circuit controlled by the movable contact for controlling the movement of said device and means operable in timed relationship with the laying and beat-up of the weft lengths for advancing said movable contact upon the operation of said loom for weaving, actuating means comprising two oppositely acting latch members for the said advancing means, said actuating means being inoperative when the loom is reversed so as to maintain the timed relationship between the advancing means and the measured length of weft.

5. In a loom having a loom stop motion and a weft supply package containing a measured length of weft, mechanism for controlling said loom stop motion upon or just before the exhaustion of the measured length of weft from the weft supply package regardless of the number of pick-outs made during the weaving in of said weft supply package and comprising an endless member operable in a rotatable cycle and in timed relationship with the loom stop mechanism during forward weaving, means comprising two oppositely acting latch members for rotating said member during the running of the loom for forward weaving and for maintaining the timed relationship between its rotational cycle and the measured length of weft regardless of pick-

outs or unweaving before exhaustion of the weft package, said last named means being operated during both the weaving and unweaving movements of said loom but operating said endless member only during the weaving movements of said loom.

6. In combination on a loom, a moving loom part, a shuttle containing a measured weft supply, means for controlling a loom stop motion upon or just before the exhaustion of the predetermined length of weft, which comprises an endless weft-counting device for counting the picks of weft laid, a one-way clutch device having a pair of oppositely acting latching members, driven from the moving loom part, and mechanism controlled by said counting device for stopping the loom, said moving loom part being operable in the reverse direction without operating said endless weft counting device.

7. In combination on a loom, a moving loom part, a shuttle containing a measured weft supply, means for controlling a loom stop motion upon or just before the exhaustion of the predetermined length of weft, which comprises an endless weft-counting device for counting the picks of weft laid, a one-way clutch device, having a pair of oppositely acting latching members, driven through reduction gears from the moving loom part, and mechanism controlled by said weft-counting device for stopping the loom, said moving loom member being operable in the reverse direction without operating said endless measuring device.

8. In combination on a loom, a moving loom part, a shuttle containing a measured weft supply, means for controlling a loom stop motion upon or just before the exhaustion of the predetermined length of weft, which comprises an endless weft counting device for counting the picks of weft laid, a one-way clutch device, having a worm gear and a pair of oppositely acting latching members, driven through reduction gears from the moving loom part, and mechanism controlled by said counting device for stopping the loom, said moving loom part being operable in the reverse direction without operating said endless weft-counting device.

9. In combination on a loom having a weft supply package of a predetermined measured length, an endless belt; a loom stop motion operating to stop the loom upon or just before the exhaustion of the measured length of weft from the supply package, regardless of the number of pick-outs made during the weaving in of said weft supply package, comprising a movable member, a device controlling the stopping of the loom and movable into and out of the path of said member, a circuit containing an electro-magnet, a contact having a rotational cycle and movable by said endless belt for controlling said circuit, and a one-way clutch mechanism comprising a pair of oppositely acting latch members for driving the endless belt during forward weaving but which maintains the timed relationship of the rotational cycle of the contact and the measured weft during unweaving.

JOSEPH P. COSTELLO.
